UNITED STATES PATENT OFFICE

LOUIS H. MORIN, OF NEW YORK, N. Y., ASSIGNOR TO DOEHLER DIE-CASTING CO., A CORPORATION OF NEW YORK

CABINET

Application filed November 29, 1929. Serial No. 410,338.

My invention relates to cabinets. In particular, the invention comprehends an ornate cabinet, the walls of which consist of a grille and backing member therefor.

5 An object of my invention is to provide an ornamental cabinet with grille walls, which is comparatively inexpensive to manufacture and readily and easily assembled.

In accordance with my invention, I construct a cabinet having walls consisting of 10 a grille and a backing member which is secured to the grille. Intermediate the backing member and the grille, there is placed a layer of fabric which is secured to the backing member. The backing member is secured 15 to the grille by perforated lock washers which are pressed over projections extending from the rear surface of the grille member through openings in the backing member provided 20 therefor.

Other advantages of my invention will appear from the following particular description of one embodiment of my invention taken in connection with the accompanying 25 drawings in which:

Fig. 1 is a front elevation of a cabinet constructed in accordance with my invention;

Fig. 2 is a side elevation of the same;

30 Fig. 3 is a transverse horizontal section taken on the line 3—3 of Fig. 1;

Fig. 4 is a sectional elevation taken on the line 4—4 of Fig. 2;

Fig. 5 is a sectional elevation taken on the line 5—5 of Fig. 1;

35 Fig. 6 is an elevation of the rear panel member of the cabinet;

Fig. 7 is a plan of the bottom member;

Fig. 8 is a detail of a lock washer used in 40 fastening the backing member to the grille;

Fig. 9 is a section of a lock washer taken on the line 9—9 of Fig. 8;

Fig. 10 is an enlarged fragmentary trans- 45 verse section taken on the line 10—10 of Fig. 1;

Fig. 11 is a like view taken on the line 11—11 of Fig. 1; and

Fig. 12 is an enlarged fragmentary section of one of the leg members.

For the purpose of illustrating my invention, I have shown it embodied in a radio cabinet; it is, however, to be understood that the invention is not limited to the particular form or type of cabinet illustrated.

The illustrated cabinet consists of top and 50 bottom members, and ornate front and side walls designed as shown. The front and side walls of the cabinet consist of an outer ornamental grille member 1 which is preferably made of metal, die-cast to the desired 55 form, a backing member 2, and an intermediate layer of fabric 3. The grille of the front wall includes a circular ornamental part 4 in the rear of which the loud speaker unit (not shown) of the radio receiving set is 60 placed, the backing member for the front wall being provided with a circular opening 5, behind the circular grille part as shown in Fig. 4. Below the circular part 4, a plate 7 is provided in which the controls 8 for the 65 receiving set are journaled. At the side edges of the front grille, short rearwardly 70 extending flanges 9 are formed which overlap the front edge of the side grille members. The lower corners of the front grille member 75 and lower rear edges of the side grille members are enlarged to form solid hexagonal base members 10 which rest upon leg members.

The side grille members are secured to the 80 front grille member by machine screws 11 which extend through inwardly extending flanges 12 formed on the front edge of the side grille members and which abut against the front grille member. Near the rear edge, 85 inwardly extending flanges 13, against which the rear wall 14 of the cabinet abuts, are formed on the side grille members. The rear wall of the cabinet, which is provided with elongated perforations for ventilation 90

purposes as shown in Fig. 6, is removably secured to the flanges 13 by thumb screws 15.

The backing members 2 and the intermediate layer of fabric 3, which may be secured 5 to the backing members 2, as by being glued thereto, are secured to the grilles by washers 16 pressed over studs 17 extending inwardly from the rear surface of the grille. The backing members which are provided 10 with openings through which the studs 17 on the grilles extend, are preferably made from pliable material such as cardboard so that they will assume the curvature of the grille when pressed into contact therewith.

15 The washers 16 which are made from hardened steel, have an internal diameter slightly less than the diameter of the studs 17 on the grille members. Radial slots are cut in the washers 16 forming tongues 18 which 20 bite into the stud 17 when the washers are pressed thereover, thereby preventing the washers from backing off of the stud.

A top member 19 and a bottom member 20 complete the cabinet. The top member 19 rests upon the upper edge of the grille members to which it is secured by screws 21 which extend through lugs 22 formed on the upper edge of the grille members and which are drilled to receive the screws. The bottom member 20 rests upon ledges 23 formed on the base members 10, the bottom member being perforated to admit air to the cabinet.

The leg members consist of tubular sheet metal members 24 bent to the desired shape. 15 The upper edges of the tubular members 24 are received in grooves in the bottom of the base members 10 of the cabinet, and a cap 25 is applied to the lower ends of the legs. The cap 25 is drilled centrally thereof to receive a through bolt 26 which extends longitudinally of the tubular member 24 and is threaded into the base member 10. The head of the through bolt 26 which is sunk below the surface of the cap 25 is covered by a button like member 27 which rests upon the floor. A brace 28 is secured to each tubular member 24 and assists in supporting the bottom member 20 to which it is secured by means of screws 29.

50 The design of the grille or shape of the cabinet is of course a matter of taste and selection and form no part of this invention which resides in the illustrated construction above particularly described and in which, it 55 is obvious that various changes may be made without departing from the spirit and scope of my invention as expressed in the appended claims.

Claims:

60 1. In a cabinet, front and side walls comprising an outer grille, studs on the inner surface of said grille, a backing member having openings therethrough to receive said studs, an intermediate layer of fabric between the backing member and the grille secured to

said backing member, and lock washers on said studs to secure the backing member to said grille.

2. In a cabinet, front and side walls comprising an outer grille, studs on the inner surface of said grille, a cardboard backing having openings therethrough to receive the studs, said backing being pliable to conform to the shape of the grille, an intermediate layer of fabric between the grille and the backing and means on said studs for securing the backing to the grille. 70

75 3. In a cabinet, a wall comprising an outer grille and a backing member, studs on the grille extending through the backing member, and lock washers on the studs for securing the backing members to the grille, the said washers being formed from a metal having a greater hardness than the studs, and having radial slots forming spring tongues, 80 the internal diameter of the washer being less than the diameter of the studs, whereby the tongues bite into the studs when the washers are pressed thereover.

85 In witness whereof, I hereunto subscribe my signature. 90
